UNITED STATES PATENT OFFICE.

WILLIAM H. FINNEY, OF NASHVILLE, TENNESSEE.

AUTOMATIC RAILWAY GATE.

Application filed May 2, 1923. Serial No. 636,221.

This invention relates to automatic railway gates.

An object of the invention is the provision of a practical and effective mechanism for automatically operating railway gates by a passing train wherein the gates are normally extended transversely of the tracks.

A further object of the invention is the provision of a device actuated by a passing train for not only operating a railway safety gate but a series of visual signals cooperating with the gate to aid in saving life at said railway crossing.

15 A further object of the invention is the provision of a device for operating a railway gate, which device is so constructed that the same may be readily and effectively actuated by a passing train for warning persons in advance of the approaching train and for swinging the gate across a blind and dangerous crossing to prevent access to the tracks.

20 Another object of the invention is the provision of a device which is not only automatically operated by a passing train to swing the gate transversely of the railway crossing but which will, in advance, warn the engineer of an approaching train when the gate fails to obstruct the crossing.

Other objects and advantages will become apparent during the course of the following description.

The invention is illustrated by way of example in the accompanying drawings, in which,

Figure 1 is a front view of the gate and the operating mechanism for the gate partly in section.

Figure 2 is a plan view partly in section of the operating mechanism for the gate.

Figure 3 is a vertical section of the jack for operating the gate to open position.

Figure 4 is a diagrammatic view of the electric wiring of the numerous circuits for controlling the visual signals and the actuation of the gate in one direction.

Figure 5 diagrammatically shows the electric control attached to the gate.

Figure 6 is a side view of a semaphore.

Figure 7 is a plan view of a gate and an auxiliary gate in open position.

Figure 8 is diagrammatically shown electric circuits and the controls for the semaphores.

Referring to the drawings, 1 designates

the casing in which the operating mechanism for the swingable gate 2 is located. The gate being movable through a circumferential slot 3 in the cylindrical portion 4 of the casing 1. An operating shaft 5 is mounted in bearings 6, 7, 8 and 9 formed in the casing. A reduced portion 10 of the shaft 5 projects beyond the tower or cylindrical casing 4 and is provided with an eye 65 11 at its upper end to receive one end of a cable 12 which is secured at its other end adjacent the outer free end of the gate 2. A warning signal light 13 is mounted on the swingable gate 2. 70

As shown in Figure 1 the gate is extended longitudinally of the tracks 14 and directly over the railroad crossing and is in closed position. A motor 15, which is adapted to be automatically set in operation in a manner which will be presently explained, is mounted in a portion of the casing and is provided with a shaft 16 having a gear 17 at its outer end. The gear 17 meshes with a gear 18 which is mounted on 80 a shaft 19. The shaft 19 is mounted in bearings in a jack casing 20 located in a pit within the casing 1 and is provided with a spur gear 21 adapted to mesh with the teeth of a rack 22 slidable within the casing 20 for opening the gate, while a pawl 23 is adapted to engage the teeth of the rack and maintain the rack in its most elevated position and the gate in open position and extended transversely of the tracks 14. 90

A magnet 24 located in a circuit 26, as shown in Figure 4, is adapted to move the arm 25 and release the pawl 23 from the rack 22 to permit said rack to descend when the gate is to be closed over the crossing 27. 95

The rack 22 meshes with a gear 28 mounted in bearings 29. A bevelled gear 30 is rigidly mounted on the same shaft as the gear 28 and meshes with a bevelled gear 31 rigidly connected with the shaft 5. 100

A bevelled gear 32 rigidly connected with the shaft 5 at its lower end meshes with a gear 33 mounted on a shaft 34. The shaft 34 extends diagonally underneath the tracks 14 in the pit 35 and operates a shaft similar to the shaft 5 for actuating a gate which is similar to the gate 2 to be extended transversely of the tracks and also transversely of the crossing 27 to warn a train approaching in a direction opposite to a train which travels on the tracks 14. 110

A platform 36, shown in plan view in Fig-

ure 2, which is located at the top of the pit 35, provides a support for the resilient bumpers 37 and 38 which are located at substantially right angles to each other.

- 5 An arm 39, which is rigidly connected to the shaft 5, is adapted to be oscillated between the bumpers 37 and 38. A chain 40 connected at one end to the outer free end of the arm 39 passes over a ball bearing roller 41 mounted on a shaft 42. The lower end of the chain 40 is connected to a weight 43 which is movable within a pit 44. When the weight 43 has moved by gravity to the bottom of the pit after the pawl 23 has been released from the rack 22, the gate 2 will likewise have been moved longitudinally of the track and transversely of the crossing 27. The motor 15 actuates the rack to its most elevated position, causing the gears 30 and 31 to be rotated and likewise the shaft 5, for moving the gate 2 transversely of the track 14 and the arm 39 in engagement with the resilient bumper 38.

Mounted on the shaft 5 is an arm 45 which is adapted to oscillate over a control board 46 which is formed rigidly with the inner wall of the tower 4. The arm is provided with contacts 47 and 48 with the contact 47 adapted to engage a contact 49 on the control board 46, while the contact 48 is adapted to engage an arcuately shaped contact 50 likewise in the control board. A movable contact 51 engageable with a contact 51^a is moved out of engagement with contact 51^a when the gate is closed. The contacts 51 and 51^a are mounted on the control 46. A movable contact 52 engageable with a contact 52^a is moved out of engagement with contact 52^a by the arm 45 when the gate is opened and located transversely of the track.

Referring to Figure 4, a diagrammatic view of a single line block system for controlling the visual signals and the automatic operation of the motor 15, is shown. A relay 53 is controlled by a short section 54 of the track at each end of the block, for ringing a bell 55 as a warning to anyone that the gate is about to close and also controls the circuits for lighting the lamp 13 on the gate 2 and the lamps 56^a in the semaphores 56. The magnet 57 is energized by the circuit 58 which is connected with the battery 59 and the short section of the block 54 and operates the relay 53.

55 A relay 60 is operated by magnet 63 when a train moves over the block 61 closing the circuit 62 which energizes the magnet 63. The track section 61^a is connected with the battery 59. The circuit between track section 61 and 61^a is made through the wheels and axle of the engine and cars passing over these sections. The magnet moves the relay 60 to engage contacts 64 and 65 closing the circuit 26, thereby energizing the magnet 24 to operate the armature 25 and release the

pawl 23 from the rack 22. The rack then moves downwardly within the casing 20 and releases the shaft 5 whereby the arm 39 is actuated by the downward movement of the weight 43 until said arm engages the bumper 37 when the gate 2 is located transversely of the crossing 27.

When the gate is moved transversely of the crossing the control arm 45 is moved to the dotted line position and contact 48 engages contact 50 thereby closing circuit 66 to the bell 55, lights 13 and 56^a. This circuit was opened when the train left block 54. Movable contact 51 which was in engagement with contact 51^a is moved out of engagement with said contact thereby breaking circuit 67 demagnetizing 24, and releasing armature 25. By the release of said armature the pawl 23 is permitted to again engage the teeth of the rack 22.

The semaphores 56 are placed on each side of the track and are controlled by a circuit 68 through the contact 47 on arm 45 engaging contact 49 on the control board in the dotted line position of arm 45. These semaphores are adapted to be illuminated to disclose a green light for showing that the track is clear when the gate is closed but if for any reason the gate does not close, the lights will slow red in the semaphore since the arm 45 could not be moved to dotted line or closed position with the gate open, therefore the contacts will not engage and the circuit 68 will likewise be open. As long as circuit 68 is open the semaphore will show red.

When gate 2 and likewise arm 45 leave their position transversely of the tracks, the spring pressed movable contact 52 engages contact 52^a thereby tending to close the circuit 69 to the motor 15 but since the armature 60 is held away from contacts by magnet 63 the circuit remains open and does so, so long as the train is on block 61. As soon as said train moves to block 54^a, the circuit through line 62 is broken, magnet 63 is demagnetized and spring 72 returns armature 60 to contacts 70 and 71. The circuit 69 is electrified and the motor is set in motion which rotates shaft 5 to raise the ball bearing jack, thereby returning the gate to its open position. As the gate returns to its open position the contact 52 is moved away from contact 52^a thereby breaking the circuit 69 to the motor. Since the pawl 23 is in engagement with the rack 22, the rack will be held in elevated position.

It is to be noted that when the train moves on block 54^a and contact 71 is engaged by armature 60 a circuit 73 is closed leading to lights 13, 56^a and bell 55 for operating these elements.

Circuit 62 leads to battery 59 as shown. A wire 74 connects track 61^a with the battery.

The lamp 13 as shown more particularly

- in Figure 7, comprises a casing 75 having two diametrically opposite red lenses 76 and 77 and two green lenses 78 and 79 disposed diametrically opposite each other but along a line which is at a right angle to line passing through the red lenses. The red lenses are so placed that they will disclose a red light to an approaching train coming from either direction when the gate is open or to 10 pedestrians approaching a crossing when the gate is closed. The green lights are displayed to an approaching train when the gate is closed and to pedestrians when the gate is open.
- 15 In Figure 8 is diagrammatically shown the system of wiring for a controlling arm 45 of a main gate and a controlling arm 45^a of an auxiliary gate with contacts 80 and 81 in a circuit 82 of a battery 83. The closing 20 of one gate and likewise the closing of the contacts 80 and 81 on that gate would not close the circuit 82 and then operate the semaphores 84 or either one since both contacts must be closed to close the circuit. 25 This form requires the closing of both gates and if some obstruction on the tracks would prevent closing of one gate, the semaphores would not be operated and therefore red lights will show.
- 30 The pairs of engaging contacts 47 and 49, 48 and 50, 51 and 51^a, 52 and 52^a operate as switches for closing the respective circuits connected with said contacts.
- What I claim is:
- 35 1. In a safety device for railroad crossings, a gate, a gate-actuating mechanism for automatically moving said gate transversely of the tracks to open position or longitudinally of the tracks to closed position, a motor 40 for moving the gate transversely of the tracks, an open circuit connected with said motor, semaphores provided with lamps adapted to show a red light, an open circuit connected with the lamps in the semaphore, means 45 caused to be operated by a moving train for closing the circuit to the lamps, and means associated with said circuit and controlled by the movable gate for closing the circuit to continue the illumination of the lamps, and means operated by the moving train 50 after said train has passed the gate for closing the circuit to the motor and causing operation of the motor for opening the gate.
2. In a safety device for railroad crossings, a gate, a motor for causing the gate 55 to be moved transversely of the tracks, an open circuit connected with said motor, semaphores provided with lamps adapted to show a red light, an open circuit connected with the lamp in the semaphore, means 60 caused to be operated by the moving train for closing the circuit to the lamps whereby said lamps are illuminated, and means operated by the moving train after the train has passed the gate for closing the circuit to the 65 motor and causing operation of the motor for opening the gate, and means connected with the gate for opening the circuit to the motor when said gate is located substantially transversely of the track.
3. In a safety device for railroad crossings, a gate actuating mechanism for automatically moving the gate transversely of the tracks to open position or longitudinally of the tracks to closed position, a motor for 75 moving the gate transversely of the tracks, lamps on the gate, semaphores provided with lamps, open electric circuits connected with the motor, semaphores and lamps, stationary contacts mounted adjacent the gate and connected with the circuits of the lamps and semaphores, contacts carried by the gate engageable with the stationary contacts to close said circuits, means operated by the moving train when said train passes the gate 85 to close the circuit to the motor whereby the motor is operated for opening said gate, means for causing closing of the gate, means automatically operated for releasing the closing means for the gate, and means connected with the gate for opening the circuit to the motor when said gate has fully opened.

WILLIAM H. FINNEY.
